CARTON

Charles K. Ellsworth, Sandusky, Ohio, assignor
to The Hinde and Dauch Paper Company, San-
dusky, Ohio, a corporation of Ohio

Application May 25, 1933, Serial No. 672,779

4 Claims. (Cl. 229—38)

My invention relates to a carton, box, or like container and has for its object to provide such container that will hold its contents firmly in place and will not require stuffing or packing with tissue or waste paper to fill inside space 5 not occupied by the article packed, so as to hold such article in place, nor require the article to be tied within the container to prevent shifting.

Other important objects of the invention are 10 to provide a container which can be quickly and easily assembled when packed, which will be self-locking without tying or the use of adhesives or other means of fastening, yet will remain securely closed, hold its rigid shape and provide safe carriage for the contents. Such a container 15 is particularly adapted for use by retail stores in packing garments, such as lingerie, hosiery and similar merchandise which must be kept flat so that it will not bunch or wrinkle, but which 20 therefore must be held firmly but not so tightly as to be crushed or creased. As further adapting my container for retail trade means may be included for enhancing the ornamental appearance of the package.

To the accomplishment of the foregoing and 25 related ends, said invention, then, consists of the means hereinafter fully described and particularly pointed out in the claims.

The annexed drawing and the following description set forth in detail certain structure 30 embodying the invention, such disclosed means constituting, however, but one of various structural forms in which the principle of the invention may be used.

In said annexed drawing Fig. 1 illustrates a 35 blank for my improved carton; Fig. 2 is a median transverse cross section of the assembled carton; Fig. 3 is a perspective view of one end of the assembled carton as formed from the blank of Fig. 1; Fig. 4 is the same section as Fig. 2, with the parts in a modified arrangement; and Fig. 5 is a longitudinal section through the assembled 40 carton on the line 5—5, Fig. 2.

The carton may be made of any suitable material, such as corrugated board, solid fiber board, 45 or the like. Although corrugated board is illustrated, it is to be understood that I do not restrict myself thereto but may use any material having characteristics suitable for the purpose.

In the preferred form of blank herein illustrated, which is subject to modification in 50 details, within the scope of the invention, the scores for folding are illustrated by various dotted lines described in detail below, and a supplemental 55 fastening means is also shown.

The carton comprises a bottom 10 having end flaps 11 and 12, and joined by sides 13 and 14 to the top 15 and an inner flap 16 respectively. End flaps 17 and 18 and a side extension 19 are attached to the top 15.

The bottom is defined by scored folding lines or creases A, B, C and D as shown and the top is similarly defined by folding lines E, F, G and H. The side pieces 13 and 14 have end tabs 20 hinged along folding lines J, these tabs being 10 slightly narrower than the width of the sides to permit the carton to be folded for assembly. The flap 19 is separated from the side element 14 by a creased folding line K. The flap 19 is creased as at L parallel to the side creases, so 15 that the outermost area 21 can be folded back over 19 as shown in Fig. 2.

Creases M, N, O and P parallel to the ends of the carton permit the respective end flaps 11, 12, 17 and 18 to be folded at the box height, so as 20 to divide these flaps into upstanding end portions and reversible tongues for tucking under when assembling the carton, as is customary in this art. The natural resiliency of materials generally used in this art causes the flaps 17 25 and 18, when tucked in, to tend somewhat away from the surface 15. Thus the flaps 17 and 18 bear against the top surface of the extension surface 19 in the assembled box and thus add to the downward spring of that extension.

A reenforcing strip 24, which will preferably be a paper or cloth tape, is indicated by dotted lines in Fig. 1 and is shown in its relation to the closed carton in Fig. 3.

As will be apparent from Figs. 1 and 2, when 35 the carton is folded the bottom 10, top 15 and sides 13 and 14 are brought into regular box formation. The flaps 16 and 19 are directed inside the box with the flap 19 overlapping. Previous to such assembly the edge 21 of the flap 19 40 is turned back as shown and suitably fastened in position, thus forming a rounded edge at L which will not injure any merchandise with which it comes in contact.

The flap 16 is of such width as to underlie that 45 portion of 19 between the outer edge of 21 and the fold line G. The natural resiliency of the material forces the flap assembly down on the merchandise in the bottom of the box. It will be understood that the merchandise is laid in 50 the bottom of the box before the box is closed and thus is positioned beneath the flap.

The end formations of the box are of customary character and are folded and tucked in as usual 55 in closing the container, except that the flaps 17

and 18 are folded in under the top 15, as shown in Fig. 5, thus avoiding an exposed cut edge of board along the ends of the top, and also giving a tighter frictional engagement with flaps 12 5 and 11. In practice, the flaps 17 and 18 may tend down somewhat from the top 15, but this will vary more or less according to the stiffness of the board used and according to how tightly the box is packed. In Fig. 3 the flap 18 is hidden 10 by the top 15, but the rounded edge is seen at F. The flaps 17 and 18 may also be bent along the lines O and P if it is desired to give them greater resiliency.

The engagement of the flaps 11 and 12 above 15 the inner flap 18 and within the angle at the folding line G effectively locks the carton in closed position by friction of the edges Q and R within the angle of the fold G and by the positive locking action of the flaps 11 and 12 above this 20 fold without any use of adhesive or other fastening means.

The tape 24 is fastened, as by pasting or otherwise, near the extreme ends of the blank, Fig. 1. Thus, when the carton is folded the tape is drawn 25 taut and is, in effect, tucked in between the edges G and K. This affords an additional reinforcing means whereby any tendency of the carton to bulge is counteracted. One or more tapes 24 may be used, positioned as desired. A further 30 advantage of the tape is that where the box surface is of a material on which printing cannot readily be done, the tape may also be used as a printing surface.

In Fig. 4 a modification of the inner flap is 35 shown in which the area beyond the folding line L, designated in the modified form as 21', is turned upwards instead of under and is allowed to stand out on an upward inclination from the main portion 19' of the modified tongue. In this 40 modification the edge or bearing surface, indicated as L', is thus smooth, so as not to injure fabrics against which it bears.

It will be seen from the foregoing that I have 45 invented a container which is particularly suitable for the purposes hereinbefore indicated, which is readily formed by the usual stamping processes from corrugated board or other suitable sheet material, which may readily be packaged and transported in the flat condition and 50 assembled expeditiously and without the need of any machinery when required for use. Fur-

thermore, the carton is adaptable to a variety of sizes and proportions, is neat and trim in appearance, may be given an ornamental outside finish if desired and may be imprinted at the factory or elsewhere, while flat, with such patterns, wording, or other matter as desired. 5

Other modes of applying the principle of my invention may be employed instead of the one explained, change being made as regards the structure herein disclosed, provided the means 10 stated by any of the following claims or the equivalent of such stated means be employed.

I therefore particularly point out and distinctly claim as my invention:

1. A container comprising, in combination, 15 two overlapping flaps fastened to the container body at contiguous edges and extending diagonally between opposite inner surfaces of the container, and side flaps engageable in the angle between the container body and one of said first-named flaps.

2. A container comprising, in combination, a flap element hinged along one edge of the container top and adapted to lie within the container at an acute angle to the top when the container 25 is closed, said element being resiliently urged towards a side of the container remote from said attaching edge, and side flaps engageable in the angle between said top and said flap.

3. In combination, a container adapted to be 30 pre-formed as a flat blank and comprising a plurality of inter-hinged surfaces, flaps adjacent two of said surfaces adapted in the assembled 35 container to overlap and to be hinged along a common edge, and tongues adapted to be tucked in the container ends to interlock with said flaps.

4. In combination, a container adapted to be 40 pre-formed as a flat blank and comprising a plurality of inter-hinged surfaces, flaps adjacent two of said surfaces adapted in the assembled container to overlap and to be hinged along a common edge, and a flexible member closely disposed across the entire ultimate outer surface of said blank, the intermediate length of said flexible member being free from said blank, whereby 45 when said container is assembled said flexible member is stretched closely therearound and its ends caught between said overlapping flaps.

CHARLES K. ELLSWORTH.
